TONSILLOTOME

William H. Irvine, Fredericton, New Brunswick,
Canada

Application October 30, 1934, Serial No. 750,619

7 Claims. (Cl. 128—309)

This invention relates to tonsillotomes and while the instrument is primarily adapted for the removal of tonsils it is also adapted for use in other surgical operations.

5 It is an object of the invention to provide an improved tonsillotome embodying an écraseur with means to position the same relative to the tonsilar space in the passage from the mouth to the pharynx with means to actuate the écraseur 10 to effect enucleation or extirpation of the tonsil by compressing the tonsil at the base or neck to prevent hemorrhage and the abscission of the tonsil pedicle.

In instruments of this character heretofore 15 there has been provided a carrier bar arranged as a handgrip at one end and the opposite extremity arranged with a member of distal fenestra form as a means to approach the tonsilar space, the écraseur comprising a strand of suitable material, preferably wire, attached at the 20 opposite ends to a slide mounted upon the carrier bar intermediate the handgrip and distal member, the wire being arranged intermediate the ends to loop form and the loop expanded and positioned relative to a recess interior of the 25 fenestra wall of the distal member and positioned about the tonsil by the distal member and said loop in the removal of the tonsil being gradually diminished or contracted to compress the 30 tonsil by moving the slide upon the carrier bar.

In such instruments the distal member is of flat 35 form with the result that when it is positioned relative to the tonsilar space only an intermediate portion of the tonsil will be embraced by the écraseur loop and it is impossible to extirpate the tonsil and only a part of the tonsil may be removed, as by cutting. It is a further object 40 of the invention to overcome this disadvantage by arranging the distal member of ovate or spoon shape, that is, of convex form in longitudinal 45 and transverse section, and offset the distal member relative to its carrier at the juncture of the distal member with the carrier, whereby the tonsilar space may be more closely approached by the distal member and position the loop of the écraseur to engage and compress the tonsil at the base or neck and assure the enucleation or extirpation of the tonsil, and the provision of means to guide the écraseur during the 50 actuation thereof.

A further object of the invention is to provide in tonsillotomes means to co-operate with the écraseur to effect an abscission of the pedicle of the tonsil enucleated or extirpated by the écraseur.

It is another object of the invention to provide the tonsillotomes with a fenestra distal member and arrange a portion of the fenestra wall with a cutting edge disposed in opposed relation to the outermost curved portion of the fenestra 5 wall and the écraseur loop when positioned in the recess in the outer portion of the fenestra wall of the distal member to co-operate with the écraseur loop during the diminishing of said 10 loop to cleave the pedicle of the enucleated tonsil thereby and effect abscission of the tonsil.

Other objects and advantages will hereinafter appear.

In the drawing accompanying and forming a part of this application, Figure 1 is a plan view of 15 my improved tonsillotome showing the écraseur wire in partially diminished or contracted position.

Figure 2 is a side elevation, partly in section, to show the connection of a thumb or finger 20 engaging member with a carrier bar for the operative parts of the tonsillotome, and showing means to releasably lock the écraseur actuating slide in adjusted position on the carrier bar and showing the same in slide releasing position. 25

Figure 3 is a longitudinal sectional view of the distal member to show the connection thereof with the carrier member, the arrangement of the écraseur wire relative thereto, and the cutting means to effect abscission of the pedicle of 30 an enucleated tonsil, the section being taken substantially on the line 3—3 of Figure 1 looking in the direction of the arrows.

Figure 4 is a sectional view, on an enlarged scale, taken on the line 4—4 of Figure 1 looking 35 in the direction of the arrows to show the arrangement of the écraseur actuating slide and the means to releasably lock said slide to the carrier bar.

Figure 5 is a cross sectional view taken on the line 5—5 of Figure 4 looking in the direction of the arrows to show the mounting of the means to releasably lock the écraseur actuating slide on the carrier bar. 40

Figure 6 is a cross sectional view taken on the line 6—6 of Figure 1 looking in the direction of the arrows to show the arrangement of the connection of the distal and bar members and the arrangement of the cutting means to co-operate with the écraseur wire to effect abscission 50 of the pedicle of the tonsil; and

Figure 7 is a view taken substantially on the line 7—7 of Figure 1 looking in the direction of the arrows to show the arrangement of guides 55

at opposite sides of the carrier bar for the engagement and guiding of the écraseur wire.

In carrying out the embodiment of the invention illustrated in the drawing there is provided a carrier for the operative parts of the device in the form of a bar 8 arranged at one end portion as a handle, the bar preferably being of rectangular shape in cross section having a reduced screw threaded shank 9 extended from one end 5 for the threaded connection of an annular thumb or finger engaging member 10. The opposite end portion is arranged of increased width, as at 11, and the extremity arranged as a member of distal fenestra form in that the end wall 15 is of arcuate form and has a circular opening therethrough with the outer end wall of the opening of annular form and extending through an arc slightly greater than 180 degrees, as shown at 12 in Figure 1, and provided in the interior 20 surface thereof with a groove or recess 13, as shown in Figure 3. The distal member is of ovoid or spoon shape in that it is of convex form in longitudinal and transverse section and is offset laterally of the carrier bar 8 substantially 25 midway the ends of the portion of increased width 11, as at 14. The wall of the opening in the distal member opposite the annular wall portion 12 is arranged as a cutter 15, the cutting edge 15' of which extends substantially in an arc 30 of 180 degrees and merging at the opposite ends with the annular wall portion 12. This cutter is formed by undercutting or recessing the upper surface of the handle at the juncture of the distal member rearwardly from the cutting edge 35 15' to a point substantially at the offset of the distal member, as at 16, thereby arranging the cutter of a thickness substantially the same as the outer convex wall of the recess 13 and said cutting edge merging in said recess wall. The 40 opposite side wall of the recess 13 is of the same width for an arc of substantially 180 degrees when it is reduced in width to less than the width of the extremities of the arcuate cutting edge, as at 12', and then merges with portions of arcuate form, as at 17, of the side wall of the undercut portion 16, the wall of said arcuate portions being recessed or undercut to constitute in effect continuations of the recess 13 and spaced apart a distance less than the diameter of the 45 opening in the distal member to extend substantially in line with guideways in the form of bores 18 through the portions of increased width at opposite sides of the carrier bar 8, the end wall of said undercut portion 16 also being recessed and 50 the end wall of the recess arranged of arcuate form, as shown at 19 in Figures 1 and 6. The cutter 15 is of concave form in cross section, as shown in Figures 3 and 6, and diminishes to flat form rearwardly from the cutting edge to where 55 it merges with the carrier bar 8. It will be obvious that by this arrangement of the distal member that the tonsilar space in the passage of the mouth to the pharynx may be closely approached by the convex surface thereof with the 60 wall of the opening in the distal member embracing the base or neck of the tonsil.

To enucleate or extirpate the tonsil and simultaneously therewith compress the tonsil at the base or neck to prevent hemorrhage an écraseur 65 of suitable material is provided, preferably consisting of a wire loop 20 formed by bending a strand of wire upon itself intermediate the ends with the opposite ends extended through the guide bores 18 whereby the loop may be positioned relative to the recess 13 in the wall 12 of

the opening in the distal member and the recesses in the parts 17, as shown in Figure 1. The écraseur loop is normally positioned and concealed within the recess 13 of the distal member, as shown in Figure 3, and to effect a gradual 5 diminishing or contraction and movement of the loop across the opening in the distal member, the opposite ends of the wire are releasably connected to an actuator mounted on the carrier bar 8. In the embodiment shown this actuator 10 comprises a slide 21 of rectangular shape in cross section having an opening therethrough conforming to and for slidable engagement on the carrier bar 8, the slide being provided with oppositely extending annular finger grips 22. The 15 actuator slide with the finger grips may be a casting, or the same may be formed of sheet metal and the finger grips secured thereto, as by welding. To releasably secure the ends of the wire to the actuator slide they are extended through 20 openings in the juncture of the finger grips 22 with the slide, as at 23, and releasably clamped to the finger grips by coiling the extremities of the wire about and below the heads of screws threaded into the finger grips, as shown at 24 in 25 Figures 1 and 2.

To releasably lock the slide against movement on the carrier bar with the écraseur loop engaging the recess 13 in the distal member or in either of its diminished or actuated positions, the actuator slide for the écraseur is provided with a locking detent to engage in either one of a series of transverse notches 25 spaced longitudinally of the carrier bar. This locking detent is shown in the form of a plate 26 of resilient material secured 30 in juxtaposed relation to the slide 21 by lips 27 extended upward from the slide and engaging over the opposite marginal side portions of the plate adjacent one end, as shown in Figure 1. The one end of the plate extends beyond the end 35 of the slide opposite the écraseur wire and is provided with a laterally extending pawl 28 to engage a notch 25 under the inherent tension of the plate.

To release the detent from a notch 25 and retain it in released position to permit of free sliding movement of the écraseur actuator slide on the carrier bar to adjust the écraseur loop to position within the recess 13 of the distal member and to diminish or contract said loop, means are 45 provided to move the pawl end of the detent plate against its inherent tension and thereby disengage the detent pawl from a notch 25 and hold said end of the detent in such position. For this purpose the opposite marginal portions of the 50 plate intermediate the attaching ears 27 and pawl end of the detent plate are arranged with eyes 29 to be disposed in parallel relation to the perforations in ears 30 extended upward from the slide 21 for the pivotal engagement of the ends 55 of a pintle 31 arranged with cams 32 disposed within the eyes 29 of the plate, the pintle being provided with an operating lever or finger grip 33. In the normal position of the actuating lever 33 it is positioned to extend in contiguous relation to the detent plate 26 with the cams out of engagement with the eyes 29 of the detent, as shown in Figure 4, the parts being retained in said position by the inherent tension of the detent plate. To move the detent pawl 28 out of 60 engagement with a bar notch the lever is actuated to the position shown in Figure 2, thereby rotating the pintle 31 and therewith the cams 32 which move the plate against its inherent tension to position the detent pawl out of engagement with a 65 70 75

bar notch, as shown in Figure 2, the plate co-operating with the cams to retain it in said position.

In operation the écraseur actuating slide 21 is released from the carrier bar to permit movement of the actuator slide upon said bar. The écraseur loop is then adjusted to position it within the recess 13 of the distal member, when the detent plate 26 is released to permit it under its inherent tension to engage the pawl 28 with a bar notch 25. With the parts in said positions the tonsilar space is approached by the convex surface of the distal member to engage the tonsil in the opening therein. With the instrument so positioned 15 the écraseur actuator slide is actuated to diminish or contract the écraseur loop which may be effected by engaging the fingers within the finger grips 22 of the actuator and support the instrument with the other hand grasping the finger grip 10, or the finger grip 10 may be engaged by the thumb of the hand the fingers of which engage the finger grips 22 of the actuator. The detent pawl 28 may be so arranged that by exerting a predetermined force on the actuator 20 through the finger grips 22 to cause the pawl to yieldingly ride over the bar notches, or the detent may be released by the lever 33 before operating the écraseur actuator, which may be readily effected by engaging the finger or thumb nail below the end of the lever 33 and exerting 25 an outward force thereon.

By the arranging of the distal member of ovate or spoon form and offsetting the distal member relative to its carrier bar, the écraseur loop may be positioned closely to the base or neck of the tonsil, and as the loop is partly contracted and moved out of the groove 13 it has a tendency to move laterally and downwardly from the distal member due to the inherent tension of the wire 30 and be forced into the tonsilar space. This diminishing of the loop is gradual and effects a compressing of the tonsil and the simultaneous enucleation or extirpation of the tonsil. Simultaneously with the diminishing of the écraseur 35 loop, it is moved relative to the cutting edge 15' and effects an abscission of the tonsil pedicle. This is efficiently accomplished by the arrangement of guiding the écraseur wire through the guideways 18 and causing a movement of the compressed tonsil relative to and in the direction of the cutting edge 15', and said cutting edge due to the concave form and the form of the cutting edge, which is in the nature of a shear edge, beveled inward from the concave side to the convex side, and the guiding of the écraseur wire 40 relative to the walls 17, causes the écraseur wire to be moved in contiguous relation to the convex face of the cutter and cutting edge and thus assuring a positive abscission of the tonsil and its pedicle by the cutter. The écraseur actuator 45 is operated until the écraseur loop is moved relative to the cutter 15, which is in the nature of a shelf, and the loop is positioned relative to the arcuate wall of the recess 19, when there will be a complete abscission of the tonsil and the tonsil 50 pedicle. Should the tonsil pedicle be tough with the result that there may not have been a complete abscission of the tonsil pedicle by the cutter 15 by adjustment of the écraseur loop to position relative to the arcuate wall of the recess 55 19 will cause such portion of the enucleated tonsil pedicle to lie relative to the shelf or cutter and in which position it may be readily snipped off by a pair of scissors.

75 It will be obvious that the parts may be read-

ily disassembled for cleaning or substitution of parts and as readily reassembled by releasing the ends of the écraseur wire 26 from the attaching screws 24 when the wire may be readily withdrawn from the guideway 18, and by the unscrewing of the finger grip 10 from the carrier bar the écraseur actuator slide 21 may be readily removed from the carrier bar.

To effect a cauterizing of the tonsil pedicle the écraseur wire may be connected in circuit with a source of electricity to effect a heating of the loop, in which case the carrier bar with the distal member, as well as the écraseur actuator slide, will be made of an insulating material, such as bakelite.

While I have illustrated and described one embodiment of my invention, it will be obvious that modifications may be made in the construction and arrangement of parts without departing from the scope of the invention, and that parts of the invention may be used without others and come within the scope of the invention.

Having thus described my invention, I claim:

1. In a tonsillotome, a handle having an end portion of increased width terminating at the end in a fenestra of ovate form having a circular opening therein and adapted to approach the tonsilar space with the fenestra wall embracing the tonsil, said fenestra opening having a recess in and extending about the outer portion of the wall of the opening and communicating at the juncture of the ovate fenestra portion with the handle with a guideway at each opposite side of and extending parallelly of the handle, a wire looped upon itself and the opposite ends extended relative to said guideways in the handle and the looped portion adapted to be positioned in the recess in the wall of the fenestra opening, and means to which the ends of the wire are attached slidably mounted on the handle and operative to move the loop relative to the fenestra opening.

2. In a tonsillotome, a wire looped upon itself intermediate its ends, a member including a handle having an end portion of increased width arranged at the end of ovate shape having a circular opening therein with a recess and guide in the outer portion of the wall of said opening for the engagement of the wire loop, a guideway at each side of the portion of increased width of the handle within the ovate shaped end and at each side of the handle merging with said recess for the engagement and guiding of the wire, and means slidably on the handle to which the ends of the wire are attached operative to partly diminish the size of and move the wire loop relative to the opening in the ovate shaped end.

3. A tonsillotome as claimed in claim 2, where-in the means to partly diminish and move the wire loop relative to the opening in the ovate shaped end comprises a slide mounted on the handle to which the ends of the wire are attached, a spring detent mounted on said member normally urged to engage one of a series of notches in the handle to releasably lock the slide against movement on the handle, and means to move and hold said detent out of notch engaging position.

4. In a tonsillotome, a wire looped upon itself intermediate its ends, a handle having at one end a distal member of ovate shape having a circular opening therein arranged with a recess

- in the outer portion of the wall of said opening for engagement of the wire loop and the inner portion of the wall of the opening arranged with a cutting edge opposed to and extending in the plane of the recess in the outer portion of the wall of the opening, and said member having guideways at each side of and within the ovate distal member merging with the recess in the wall of the opening in the distal member 5 for the engagement of the opposite end portions of the wire and guiding of the wire loop, and means to which the opposite ends of the wire are attached slideable on the handle and operative to partly diminish and draw the wire loop 10 across the opening in the ovate distal member and relative to the cutting edge to compress and extirpate the tonsil and effect abscission of the tonsil pedicle.
5. In a tonsillotome, a wire looped upon itself 20 intermediate its ends, a handle having a portion of increased width at one end terminating at the end in a distal member of ovate shape having a circular opening therein with a recess in the outer portion of the wall of the opening 25 for the engagement of the wire loop and the wall of the opening opposed to the recessed wall portion arranged with a cutting edge, a guideway arranged at each opposite side of the portion of the handle of increased width within the ovate distal member merging with the recess in the outer wall of the opening for the engagement and guiding of the wire at opposite sides of the loop, and means to which the ends of the wire are attached mounted on the handle and operative to partly diminish and draw the wire loop 30 transversely of the opening and relative to the cutting edge to compress and extirpate

the tonsil and effect abscission of the tonsil pedicle.

6. A tonsillotome as claimed in claim 5, where-in the face of the handle at the juncture of the ovate distal member with the handle is recessed 5 to form the cutter and the cutter is of concave form in cross section in opposed relation to the convexity of the ovate distal member with the concavity of the cutter diminishing to flat form rearwardly from the cutting edge, and the side 10 walls of said recess being arranged with recesses to guide the wire loop relative to the cutting edge to co-operate therewith to effect a cleavage of the tonsil.

7. In a tonsillotome, a bar arranged with an 15 arcuate distal portion of ovate form having an opening therein, a cutting edge arranged on the inner portion of the wall of said opening, a guideway in the outer portion of the wall of the opening opposite the cutting edge the opposite 20 end portions of which guideway intersect the opposite ends of the cutting edge and extend in a direction toward and terminate at each opposite side of the bar, a member slidably mounted on the bar, means to releasably retain 25 said member against movement on the bar, and a wire looped upon itself intermediate the ends with the opposite end portions extending relative to the guideway and attached to the member slidably on the bar and the looped portion 30 adapted to be positioned in the portion of the guideway extending relative to the outer portion of the wall of the opening, and the size of the loop portion of the wire adapted to be reduced and drawn across the opening in the distal portion 35 and relative to the cutting edge by the member slidably on the bar.

WILLIAM H. IRVINE.
